UNITED STATES PATENT OFFICE.

FREDERICK E. POOR, OF DARIEN, CONNECTICUT, ASSIGNOR TO PITNEY-BOWES POSTAGE METER COMPANY, OF STAMFORD, CONNECTICUT, A CORPORATION OF DELAWARE.

MOISTENER FOR ENVELOPE SEALERS, ETC.

Application filed February 24, 1927. Serial No. 170,566.

This invention is a novel device for applying moisture or liquid to objects, and is particularly designed for moistening the flaps of envelopes prior to sealing same, and 5 may be used in connection with various types of envelope sealing machines.

The object of the invention is to provide a moistener construction which will be operatively positioned by the flap of the envelope 10 being passed through the machine. With this invention the water, or other liquid, can be taken directly from the reservoir and applied to the part to be moistened without using the brush, wick or other moistening device, as a duct through which the liquid is 15 fed. This prevents clogging up of the moistener with any impurities which the liquid may contain; and the moistener being made of suitable material, a sufficient quantity of 20 the liquid will be carried by it to wet the flap of the longest envelope it is designed to seal. The invention insures an immediate and sufficient supply of liquid at all times, as the moistener is always partially immersed, 25 when not in use, in the liquid in the tank or reservoir in which a constant liquid level can be maintained.

Another novel feature of the invention is having the brush or moistener yieldably or 30 removably mounted so that it can be lifted into operative position by the flap of each envelope passing thereby, and then drop back into the tank for replenishment with the remoistening liquid after each operation.

In the accompanying drawings I have illustrated one practical embodiment of the invention and will describe the same with reference thereto, but I do not consider the invention limited to the specific construction 40 shown and refer to the claims for summaries of the essential and novel features of construction and combinations of parts for which protection is desired.

In said drawings:

45 Figure 1 is a plan view of an envelope moistener with the feed belt and part of the table broken away to show the moistening device.

Fig. 2 is a front elevation of said moistener, 50 partly in section.

Fig. 3 is an end elevation of the moistener looking from the left toward the right of Fig. 2.

Fig. 4 is a detail view showing how the

moistener device is operatively controlled by 55 the flap of a passing envelope.

The machine shown in the drawings may be part of an envelope sealing machine of any suitable construction, only the parts thereof directly relating to the moistening means being shown. In said drawings, 1 designates a plate upon which the envelopes are laid, preferably face downward and moved endwise to and beyond the moistening device. The plate 1 may be attached by a bracket 2 or 60 other suitable device to a support or back 3, and the inner end of plate 1 extends to and partly over a tank 22 in which the moistener 20 is located.

In line with the plate 1 and forming a continuation thereof beyond the moistener is a second plate 11 over which the moistened envelopes are passed and their flaps closed in so doing. The plates 11 may also be mounted on the support 3 in any suitable manner. The 65 support 3 may be of any suitable construction.

The rear edge of the plate 1 is preferably spaced from the support 3 sufficient to permit the flap *e* of an envelope *E*, laid upon the 70 plate 1, to depend below the table and between the rear edge of the plate 1 and the support 3.

The left hand end of table 11 is curved 75 downward at 11^a and a space is left between 80 the ends of tables 1 and 11 for a purpose to be explained hereafter.

A tank 22 is arranged beneath and adjacent to the inner end of plate 1, and within this tank is movably mounted a moistener 20, 90 by means of which water or other liquid is supplied from the tank to the flap of the envelope. Preferably the moistener 20 extends transversely of the plate 1 in the path of the flap of the envelope and the moistener is pivoted at 20^a, on a block 21 secured to the under side of plate 1 near the inner end thereof, the moistener being capable of a gravitational swinging movement transversely of the plate.

As illustrated in the accompanying drawings, the moistener 20 is provided with a brush 20^a by which the liquid is transferred from the tank to the envelope. While I consider a brush preferable, it is not essential to the correct functioning of the device, as felt or other material may be used in place of the brush and might answer the purpose as well or better.

The tank 22 is mounted on the support 3 and is preferably connected by a tube or pipe 22^b with a suitable reservoir (not shown in drawing), and a constant water level can be 5 maintained in the tank by means of an inverted bottle or similar device as usual. A stop 22^a in the tank 22 limits the distance to which the moistener 20 may drop. By varying the normal water level in the tank 22, 10 a greater or less amount of liquid may be applied to the moistener 20.

A guide plate 23 is secured to the frame 3 under plate 1. The left hand end of said guide plate is vertically disposed, but the 15 plate is gradually twisted until its right-hand end is substantially horizontal, said right-hand end overlying the adjacent curved side of the tank 22. The right side of tank 22 slopes upward in the direction of plate 11, 20 its edge overlying the lower curved portion 11^a of said plate.

The envelope E may be fed along the plates 1 and 11 endwise and flap down by hand or by mechanical means. In the example shown the envelopes are fed longitudinally of the plate 1 and over the moistener and outer plate 11 by means of upper and lower coacting endless belts 9 and 10. The belt 9 runs over pulleys 8 and 18 respectively 25 mounted on spindles 8^a and 18^a, suitably supported respectively beneath the plates 1 and 11. As shown, the spindle 8^a may be fixed and the pulley 8 rotatably mounted thereon. The spindle 18^a is preferably a driven spindle, and 30 pulley 18 is attached thereto. The spindle 18^a may be driven by hand or by power, and it is not necessary to illustrate the same hercine.

The belt 10 runs over pulleys 6 and 16 40 respectively mounted above the pulleys 8 and 18. The pulleys 6 and 16 may be rotatably mounted on studs 6^a and 16^a attached to swingable brackets or arms 4 and 14 pivotally mounted upon a stud 5 attached to the 45 support 3. The swinging brackets 4 and 14 may be yieldably pressed by a spring 4^s downward or toward the opposed rollers 8 and 18. The plates 1 and 11 may be slotted as shown in the drawings to accommodate 50 the belt 9.

Operation.

The envelopes E are successively placed on the plate 1, with their open side toward the 55 support 3, and their flaps projecting downward between the table 1 and frame 3. They are then fed one at a time, either mechanically or manually, toward and between the rollers 6 and 8 and 16 and 18 where they are 60 firmly gripped by and between the belts 9 and 10 and moved forward to and past the moistener and outer plate 11.

In moving forward (from left to right in the drawing), the hanging flap e of the 65 envelope E engages the guide plate 23 and

is turned directly from a vertical to an approximately horizontal position; as it reaches the tank 22 and in its passage over the tank it engages the moistener 20 and raises same to the position shown in dotted line in Fig. 70 2, and in full lines in Fig. 4. The moistener is thus raised into position between the flap e and the body of the envelope E and deposits some of the liquid (with which it is charged during its partial immersion in the 75 liquid tank) along the moving flap. The plate 1 extending between the moistener and the body of the envelope will prevent the latter from being moistened at the same time. 80

After passing the moistener the flap of the envelope is forced upward by engagement with the inclined rear side of the tank 22 and the downwardly curved inner end 11^a of plate 11; and the moistened flap is in this 85 manner brought into contact with the body of the envelope and closed, and the final sealing may be completed in any desired manner.

I claim:—

1. In envelope moistening mechanism, a 90 movable moistener, means for guiding an envelope past the moistener, and means whereby the flap of the envelope is caused to engage and move the moistener into operative engagement with such flap as the envelope moves 95 therest.

2. In envelope moistening mechanism; a water supply, a movable moistener normally contacting the water supply and means for guiding an envelope past the moistener and 100 means whereby the flap of the envelope is caused to engage and move the moistener into operative engagement with the flap as the envelope moves therest.

3. In envelope moistening mechanism; a 105 water supply, a movable moistener normally contacting the water supply, means for feeding envelopes past the moistener with the flaps underneath and means whereby the flap of each envelope is caused to engage and lift 110 the moistener out of the water supply into operative engagement with the flap as each envelope moves therest, the moistener returning to the supply for remoistening after each operation. 115

4. In envelope sealing or moistening mechanism in which the envelope is fed horizontally with the flap underneath; a water supply over which the envelope is guided, a yieldably mounted moistener engaging the 120 supply, and means for so guiding the envelope flap under the moistener that the moistener is moved into operative position by each flap as it passes, said moistener being free to return to said water supply for remoistening 125 after each operation.

5. In envelope moistening mechanism in which the envelopes are fed horizontally with the flap undermost; a water supply over which the flap of the envelope is guided; a 130

- yieldable moistener receiving water from said supply and means for guiding the envelope flap to and underneath the moistener, said moistener being yieldably mounted so that 5 the flap of each envelope is caused by the guiding means to move the moistener upwardly into operative position as it passes thereby; said moistener returning the supply for remoistening after each operation.
- 10 6. In envelope moistening mechanism; a water supplier, a movable moistener normally contacting the water supplier, means for feeding envelopes past the moistener and means whereby the flap of each envelope is caused to engage and move the moistener into operative engagement with the flap as each envelope moves therewith, the moistener returning to the water supplier for remoistening after the flap has passed.
- 15 7. In envelope sealing or moistening mechanism in which the envelope is fed horizontally with the flap underneath; a water supplier over which the envelope is guided, a yieldably mounted moistener normally engaging the supplier, and means for so guiding the envelope flap under the moistener that the moistener will be moved into operative position by the flap as it passes and permitted to return to said water supplier for remoistening after the flap passes. 25
- 20 8. In envelope moistening mechanism in which the envelopes are fed horizontally with the flap undermost; a water supplier over which the flap of the envelope is guided; a moistener receiving water from said supplier; said moistener being yieldably mounted and means for so guiding the envelope flap to and underneath the moistener whereby the flap of the envelope is caused to move the moistener upwardly into operative 30 35 position as it passes thereby; said moistener returning to the supplier for remoistening after the flap passes. 40

In testimony that I claim the foregoing as my own, I affix my signature.

FREDERICK E. POOR.
